UNITED STATES PATENT OFFICE.

CARL CHRISTIAN MEINZOLT, OF PADDINGTON, NEW SOUTH WALES, AUSTRALIA.

TUNING DEVICE FOR PIANOS.

1,257,512.

Specification of Letters Patent. Patented Feb. 26, 1918.

Application filed July 21, 1914. Serial No. 852,295.

To all whom it may concern:

Be it known that I, CARL CHRISTIAN MEINZOLT, subject of the King of Great Britain and Ireland, residing at 961 Cameron street, 5 Paddington, New South Wales, Australia, have invented new and useful Improvements in Tuning Devices for Pianos, of which the following is a specification.

This invention has been devised with a 10 view to increase the resonance and the volume of sound in piano-fortes and particularly an upright piano. For this purpose many small improvements have been made in the details of construction of a piano, but 15 the main features of improvement are centered in the sound board and in an entirely new method of stringing a pianoforte, such method of stringing also affording greater facilities for tuning.

20 In order that the invention may be properly understood reference will now be made to the accompanying sheets of drawings, in which:—

Figure 1 is a front elevation of the metal 25 frame or string plate.

Fig. 2 is a front elevation of the sound board, secured to the wooden frame at the back, with an edge view of one of the full-length ribs behind the sound board.

30 Fig. 3 is a rear elevation of the same, with an edge view of the sound board and one of the ribs.

Fig. 4 is a front elevation of the stringing 35 appliances for the last five treble notes.

Fig. 5 is a vertical section of the same on the line 5—5 of Fig. 4, looking in the direction of the arrow.

Fig. 6 is a front elevation of the stringing 40 appliances for the unicord and bicord notes in the bass.

Fig. 7 is a vertical section of the same taken on the line 7—7 of Fig. 6.

Fig. 8 is a perspective view of a full tricord set of strings in the treble.

45 Fig. 9 is a front elevation, showing how the back of the bass wrest plate is punched with holes.

Fig. 10 is a front elevation, showing how 50 the back of the treble wrest plate is punched with holes.

Fig. 11 shows in perspective, and isolated, the three slides for a tricord string, and a cross section of the nut that sits astride of the lowest and central slide for a tricord 55 string.

Fig. 12 is a cross section of one of the bass

slides, the nut that sits astride and the zig-zag blocks that will cant the nut to an angle of 60 degrees with the base.

In Fig. 1, A is the metal frame or string 60 plate, B the treble wrest plate and C the bass wrest plate. This figure shows the location of the two wrest plates, and the curve in the bridge and in the treble plate B. The highest treble string is shown at a, the lowest 65 string at a', the highest bicord string at b, the lowest unicord string at b', the bass hitch plate is shown at c, the treble hitch plate at c'.

In the sound board D, Fig. 2, which is 70 made four square, the perforations, for the passage of bolts and other appliances, are made, as nearly as possible, on the lines of the grain of the wood, and a little larger in diameter than the bolts and the like, which 75 traverse them, so as to reduce the resonance of the sound board as little as possible and prevent the wood splitting. The three pitch pins d* of each of each set that are driven into the treble belly-bridge D' are arranged 80

on a line which is parallel with a tangent to the curve of the bridge or scale rib J at the point where the center wire crosses the said rib, so that all wires in one tricord note shall be exactly the same length between the rib J 85 and pitch pins d* on the belly-bridge D'. The treble belly-bridge is shown at D', the bass belly-bridge at D². The upper part of the sound board D is bent into a reverse curve toward the rear as shown in the edge 90 view at Figs. 2 and 3, the curve starting at a point above the belly-bridge and under the highest treble strings. The back ribs d are diminished in depth, where the reverse curve occurs, as shown at d'.

The sound board is 95 placed in front of the wooden frame A', and behind the string plate A to which, and to the wooden frame, it is secured in any suitable manner. The sound board is bent backward in a reverse curve in order that adequate space may be provided for the stringing appliances, as may be specially clearly seen by reference to Fig. 5 of the drawings.

In connection with the treble, or tricord, stringing appliances, a curved wrest plate 105 B, made of rolled mild steel, is secured to the string plate A in the opening in the upper part of the latter, in the position shown at B in Fig. 1. The bottom edge of this opening is inclined downward toward the front 110 at an angle of 45°, the top edge being also inclined upward at an angle of 10 degrees.

The way in which the treble wrest plate B is secured to the metal frame A is shown at Fig. 5.

In cross section, the wrest plate B is made with two steps, a shallow step B' and a deep step B², each step being set at a downward angle of 45 degrees, while the backs are set at an upward angle of 90 degrees with the steps, as shown in Fig. 5. The edges of the steps make regular curves struck from a common center, concentric with the bridge J, as shown at B, Fig. 1, throughout the treble or tri-cord part of the piano. The back of the plate B is punched with holes b³ in the manner shown at Fig. 10. A brass frame E with a bottom plate e, a top plate e' and vertical partitions e², all tenoned together, is laid on the lower step B', thus dividing the step, by the partitions e², into a number of separate compartments, generally about sixty in number, equal to the number of tri-cord notes in a piano. This construction will best be seen in the perspective view, Fig. 8. The bottom plate e of the frame E, is bolted to the step B' by a flat headed rivet e³. The partitions e² must be radial with the curve of the edge of the step, i. e., with the common center. A slide F of oblong section but narrower at the back than at the front, is laid on the floor e of each compartment; in the top of each slide F is a recess, as shown by the section of the slide and the nut in Fig. 11. The slide F does not touch the sides e² of the compartment with which it is connected. Sitting astride the slide F, is a nut G, the underside of which is made with a projection corresponding to the recess in the slide F, so that, if the nut is moved in either direction, the slide F will move with it. The nut G makes an easy fit with the internal surfaces of the compartment; the sides of the nut G are extended so as to embrace the sides of the slide F. A female screw is threaded, left-handed, through the center of the nut G, such female screw being adapted to engage with a male screw H, in the forward end of which is a square hole h to receive the solid end of a tuning key, the arrangement being such that it is the exact opposite of the appliance used to tune an ordinary piano, where a box key is required to fit over the square heads of the pins. The rear end of the male screw H is provided with a head h' so that the head h' may be passed through the lower and larger part of one of the holes b³, punched in the back part of the wrest plate B, (Fig. 10) and the neck of the screw then pushed up to the top of the narrow curved part of the hole b³, so that the head h' may have a purchase against the back of the plate B. The female screw in the nut will then be engaged with the forward end of the male screw H, the nut will be laid astride of the slide F and the nut screwed

up, by turning the male screw H with the tuning key 2 (Fig. 5), until the wire attached to the end of the slide F is taut. The slide F has a recess f in each side, just behind the extreme forward end or nose f' of the slide, so that the other wires belonging to that tricord note string may pass, one on each side of the center wire, under the nose f', and the proper distance apart of the three wires be maintained. The above description referring to the slide, the nut, the male and female screws, relates mainly to what is installed upon the shallow step B' which only carries the appliances connected with the central wire l of a tri-cord string. 75

The appliances connected with the other wires of a tricord are the same in principle and in all their main features, but vary in detail, owing to the somewhat different conditions under which they operate. Upon the upper and deeper step b² is laid a frame E' similar in all its main features to the frame E already described in connection with the shallow step B'. Upon this upper frame E' is laid another frame E² similar in all respects to the other frames. The bottom plate of the compartment frame E', will be riveted to the step B² and the bottom plate of the frame E² will be riveted to the top plate of the compartment frame E². The centers of the compartments in the frame E' will be a little to the right of the centers of the compartments in the frame E, and the centers of the compartments in the frame E² will be a little to the left of the centers of the compartments in the frame E, i. e., the centers of the compartments in each frame will respectively be exactly in a line with the wires in a tricord string with which that particular frame is associated. Each of the slides F, F', F² (as shown in Figs. 8 and 11) is of a different shape, owing to the different positions they occupy. It will be remarked that the top plate e' of the frame E is in the same straight line with the step B², i. e., it will make part of the same super- 110 surfaces with the step B². Each frame E, E' will be riveted to the step with which it is associated, but, nevertheless, there will be a strong upward pull by the outer wires of the tricord upon the nose f' of the slide F, tending to force the top plate e' upward. This will be counteracted by providing each of the upper and outer slides F', F², with a toe or presser foot f², f³ so that the pull upward of the outer wires in the tricord upon the nose f' of the slide F, shall be counteracted by the downward pressure of the toes f², f³ upon the plate e'. 115

The rib J is located over the lowest front salient angle of the wrest plate B; all the wires will pass over the rib J downward to the pitch-pins d* on the belly-bridge D', and thence to their respective hitch pins below. The front end slide F will be made of suffi- 125

cient length for the nose f' to overhang the rib J , so that, in the stringing operation, the wires may be readily passed behind the nose f' without bending or twisting them. The 5 central wire l will be passed through an oblique hole under and behind the nose f' and hitched to a pin f'' above, while the other two wires will pass, in the recesses f , behind the lateral extensions of the nose f' 10 to the front ends of their respective slides above. All the wires will therefore pass direct from the nose f' of the slide F over the rib J to their respective pitch pins d^* on the belly-bridge D' below, and thence to their 15 respective hitch pins on the string plate A . The central wire l which is fastened to the lowest slide will be absolutely independent (so far as its manipulation is concerned) of the other two wires with which it is associated to form one tricord string. It will 20 be hitched to a separate hitch pin l' below on the string plate. The second wire m and the third wire n , or flank wires are really one continuous wire the upper ends of which are 25 hitched, one end to the slide F' and the other end to the slide F'' , thence they pass downward behind the nose f' of the slide F , over the rib J downward to their respective pitch pins d^* on the belly-bridge D' below, then 30 they will form a loop around a large hitch pin n' below the central hitch pin l' . The hitch pin n' should be of a diameter approximately equal to the normal distance between the wires m and n . The front edge of the 35 top plate c^2 , of the compartment frame E will be recessed at intervals so as to permit the flank wires m , n of the tricord strings to pass freely (without fouling the edge of the plate c^2) from the front ends of their respective slides F' , F'' , direct to the nose f' 40 of the slide E , beneath which they will pass before they reach the rib J . It is important that each pin in each set of pitch pins d^* should be the same distance from the rib J . 45 This is accomplished by arranging the three pins of each set in a row disposed so that a straight line passing through all of the pins will be parallel to a tangent drawn to the rib J at the point where the central wire of each 50 set crosses said rib.

The bass strings are some of them bicords and some of them are unicords. Moreover, the bass strings are not set radially from a common center, but parallel to one another, 55 consequently, certain structural modifications must be made in the bass wrest plate C in order to meet the altered conditions. But, although the construction of the bass wrest plate C is somewhat modified, the principle 60 involved is exactly the same. To the back of the frame A , at the bass end (Fig. 7) is secured a rolled steel wrest plate O , with one short step o in it. This plate will constitute the backs of both sets of compartments, but the upper compartments will be

partly supported on the short step. Upon a shelf near the top of the frame A is laid a zig-zag or stepped surface P , the long lines of the zig-zag being at an angle of about 30 degrees with the base line. Their surfaces 70 will constitute the surfaces for the slides. Above the lower compartments will be laid a plate P' having zig-zag surfaces above and below it, the zig-zag surface below the plate P' will form the tops of the lower compartments, while the zig-zag surfaces above will form the bottoms of the upper compartments. A similar zig-zagged plate P^2 will be placed above the upper compartments and will form their tops. Against the sides of 75 the stepped floors will be laid the partitions p forming the compartments for the slides and the nuts. No alterations of importance will be made in the slides, in the nuts or in the screws, these several parts working together in the same way as those previously described. The arrangement of the punched holes o' in the back plate O is shown in Fig. 9. The several parts are tightened up and kept together by wedge blocks Q bolted 80 to the straining plate O behind. Similar wedge blocks K pressing upon a plate K' , are applied to the treble wrest plate B , over the top plate of the uppermost compartment frame E^2 , (Figs. 4 and 5). 85

It will be remarked that whereas the nuts G of the tricords are operated, for tuning purposes, at an angle of 45 degrees from below, the nuts of the bicords and unicords are 90 operated from the same level, *i. e.*, horizontally, as may be seen by reference to Figs. 6 and 7.

The several devices hereinbefore described, viz: the large four-square bent sounding board, the appliances for maintaining the 105 wires in one tricord or bicord string at the same length, and the special mode, hereinbefore described, for stringing and tuning a pianoforte will combine to produce a full-toned, true and resonant sound, when any 110 note is struck.

I claim—

1. In pianofortes, a string plate having an aperture near the treble corner thereof, the inner edge of such aperture being inclined transversely of its length at an angle of 45 degrees and both the inner and outer edges being curved longitudinally, the curves being struck from a common center located outwardly thereof, in combination 115 with a rolled metal wrest plate having steps bent to curves struck from the same common center.

2. In upright pianofortes, a string plate having an aperture, a rolled metal wrest 125 plate mounted in the said aperture and being of such a cross section that it is formed into two steps, a shallow and a deep step, the edges of the steps being bent in curves struck from a common center, the top of the 130

wrest plate being secured to the back of the string plate and the bottom being secured to the front of the latter.

3. In upright pianofortes, the combination 5 with a rolled metal wrest plate provided with steps having their edges bent to curves struck from a common center, of a frame having a top plate and a bottom plate which are bent concentric with the curves of the steps 10 in the wrest plate, and division plates disposed at regular intervals between the top and bottom plates, the said division plates being radial with the said common center, and the top, bottom and division plates being 15 joined to form separate compartments.

4. In upright pianofortes, the combination with a wrest plate provided with steps, the backs of the steps having holes therein, of frames secured to the steps and including 20 bottom plates, slides adapted to slide over the bottom plate of the compartments, nuts straddling the slides and loosely connected therewith so that the slides and nuts may move together, male screws engaged with 25 the female threads of the nuts, the said male screws being extended through the holes in the backs of the wrest plate steps and having heads disposed in rear of the said backs to sustain the screws under longitudinal 30 stress, and means provided on each male screw for the accommodation of a tuning key.

5. In pianofortes, stringing appliances comprising in a tricord, three slides, three 35 nuts, one astride of each slide, three female screws, one in each nut, three male screws, one engaging each female screw, a keyhole in the front end of each male screw, means at the back of the male screw whereby it 40 may be retained in a fixed position and yet be able to turn when acted upon by a key, and means for securing a wire to the fore

end of each slide, as and for the several purposes herein set forth.

6. In upright pianofortes, stringing appliances for a tricord installation including 45 slides to which the wires are hitched, comprising two side slides and a central slide situated lower than the others, the central and lowest slide having recesses in its opposite sides near the front and terminating in a nose under which the wires from the other two slides pass.

7. In upright pianofortes, stringing appliances for a tricord installation including, 55 in combination with a wrest plate the top and bottom plates of a frame on the wrest plate, three slides, to the front ends of which the wires are hitched, comprising two side slides situated at different heights, and 60 a central slide situated lower than both of the others, the central and lowest slide terminating at the front end in a nose under which the wires from the other slides pass, the slides being mounted on the bottom 65 plates of separate compartments, a short toe or pressure foot formed on the side slide which is disposed between the remaining slide, and the highest slide having a long toe or presser foot, such toes or presser feet 70 being adapted to press down upon the top plate of the compartment with which the lowest or central slide is associated.

8. In upright pianofortes, the combination of a wrest plate for the bass bicord 75 and unicord strings, frames mounted on the said plate and having their bottoms set at a predetermined angle, slides movable on the bottoms, and means for adjusting the slides.

CARL CHRISTIAN MEINZOLT.
